(57) CLAIM

The ornamental design for a pocket towel with loop attachment as shown and described.

DESCRIPTION

FIG. 1 is a front perspective view of a pocket towel with loop attachment showing my new design;

FIG. 2 is a back perspective view thereof;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof;

FIG. 9 is another back view of the pocket towel with loop attachment of FIG. 1 with the pocket in a folded position;

FIG. 10 is another back perspective view of the pocket towel with loop attachment of FIG. 1 in a position of use; and,

FIG. 11 is another front perspective view of the pocket towel with loop attachment of FIG. 1 in a position of use.

The broken lines outside of the pocket towel in FIGS. 10 and 11 depict environmental subject matter that forms no part of the claimed design.

1 Claim, 11 Drawing Sheets
